(57) **CLAIM**

The ornamental design for a combination light and base, as shown and described.

DESCRIPTION

FIG. 1 is a perspective view of a combination light and base showing my new design;

FIG. 2 is a front elevational view thereof; and,

FIG. 3 is a top plan view thereof.

The broken-line disclosure in the views illustrate either portions of the article which form no part of the claimed design or an unclaimed boundary between claimed and unclaimed portions.

1 Claim, 3 Drawing Sheets

FIG. 1

FIG. 2

FIG. 3
